ELECTRIC DRAFT CONTROL GAUGE

Morris W. Crew, Shaker Heights, Ohio, assignor
to The Hotstream Heater Company, Cleveland,
Ohio, a corporation of Ohio

Application April 19, 1941, Serial No. 389,305

6 Claims. (Cl. 200—56)

This invention relates to improvements in control instruments and especially to apparatus for actuating control switches in response to variations in draft or pressure.

One of the objects of the present invention is to provide novel means for making and breaking electric circuits in response to movements of a flexible diaphragm.

Another object of the present invention is to provide an oscillating arm indicating variations of draft or pressure and a fixed arm adapted to be set at a predetermined point in the range of draft or pressure variation, and a control device actuated by relative movement between the arms. More particularly an oscillating disk is mounted on the movable arm as an axis and this disk is abutted by the fixed arm at a point spaced from the center of the disk so that relative movement between the arms causes rotation of the disk and actuation of a mercury switch carried by the disk.

Other objects and advantages will appear from the accompanying drawings and description and the essential features thereof will be summarized in the claims.

In the drawing, Fig. 1 is a front elevation of a device embodying my invention with the front of the casing removed so as to better show the parts; Fig. 2 is a sectional view through the same taken along the line 2—2 of Fig. 1 and with the front of the casing in position; Fig. 3 is a fragmental sectional view similar to the upper portion of Fig. 2 and showing another position of the parts; Fig. 4 is an enlarged fragmental sectional view taken along the line 4—4 of Fig. 1; while Fig. 5 is a wiring diagram illustrating one use of my device.

As shown in the various views, within a casing 10 is mounted a base member 11 forming a pressure chamber, the top of which is closed by a flexible diaphragm 12 held upon the base member by means of the frame or ring 13. Mounted on the base member as by means of pedestal members 14 is a U-shape bracket 15 having front and rear parallel bracket arms rigidly connected together by the spacer bar 16.

At the upper end of the rear arm of bracket 15 is mounted a stud 17 in the free end of which is inserted a stub shaft 18 as best seen in Fig. 4. Pivotaly mounted on this shaft is an arm 19 on the outer end of which is oscillatably mounted a disk 20 which oscillates about the arm 19 as an axis. Mounted on the face of this disk are mercury switches 21 and 22. As best seen in Figs. 2 and 3, switch 21 makes connection of its electric contacts when the mercury of the bulb is tilted toward the right-hand end thereof and bulb 22 makes contact when the mercury thereof is tilted toward the left-hand end thereof. The contacts of these switches are connected by very flexible wires to binding posts 23, 24, 25 and 26.

5 A pointer 27 moves with the arm 19 across a scale 28 carried on dial 29 which is mounted on the front arm of bracket 15. A link 30 has a clevis connection at 30a with the arm 19 and is suitably connected at its lower end with the diaphragm 12. Thus vertical movement of the diaphragm causes oscillation of arm 19. A counterweight 31 balances arm 19, disk 20, switches 21 and 22 and the connection 30 about the axis 18. Counterweight 32 balances pointer 27 so that with these parts and no others connected the pointer 27 would remain in practically any position to which it was moved. A rod 33 rigid with arm 19 extends vertically downward when the pointer 27 is at zero on its scale and a pendulum weight 34 tends to hold the pointer in zero position, and movement of the diaphragm 12 and the pointer 27 in response to changes in draft is opposed by the weight 34. This portion of the instrument therefore provides a very delicately balanced, practically frictionless indicating device giving accurate indications over the scale 28 and not requiring the use of any springs.

20 Another arm 35 is pivotally mounted on shaft 18 and extends outwardly substantially parallel to arm 19 where the free end of this arm passes through a slot 20a in the disk 20. On the other side of shaft 18 this arm is pivotally connected at 36 by means of a clevis 37 and a rod 38 with an adjusting knob 39 on the outside of the casing 10. By means of said adjusting knob 39 the position of arm 35 is fixed. A pointer 40 movable with arm 35 indicates on scale 28 the point selected which is the draft or pressure to be maintained by the instrument.

25 A wiring board 41 is secured to the rear arm of bracket 15 and carries the binding posts previously described and also the posts 42 and 43 to which an outside source of electricity may be connected, and binding posts 44, 45 and 46 to which a controlling motor or the like may be connected. On the front wall of the casing 10 may be mounted a control knob 47 for controlling a switch blade 47a which may have several settings as indicated 30 diagrammatically in Fig. 5. In other words there is a position for automatic control which is the setting shown in Fig. 5; there is another setting for maximum movement of the control device; another one for minimum movement of the control device; and an "off" position of the switch.

35 One use which I contemplate for my device is the control of a draft damper by a device connected to the posts 44, 45 and 46 so as to maintain a predetermined draft as set by the pointer 40. This draft will be measured in the pressure chamber 11 and will be indicated at the pointer 27. Variations of the pointer 27 away from the pointer 40 will indicate variations of the draft from that which is desired and these same variations will cause relative movement between the

arms 19 and 35. Obviously with the parts in the position indicated in Fig. 2 there is no contact at either of the mercury switches and no movement of the control device is called for. However upon movement of arm 19 in a counterclockwise direction from the position shown in Fig. 1 the parts will move as indicated in Fig. 3 because of the fixed arm 35 engaging in the slot 20a. As the arm 19 carries the center of disk 20 downwardly as viewed in Fig. 3, the disk is caused to rotate slightly making contact at the right-hand end of switch 21. This causes a flow of electricity as follows in Fig. 5: From L₁ and binding post 42 through line 48, switch 47a, line 49, binding post 24, switch 21, binding post 23 and lines 50 and 51 to binding post 44. L₂ is already connected through post 43 and line 52 with post 45. Thus one circuit of the control device connected between posts 44 and 45 is energized to cause a suitable movement of the control damper or the like thus tending to bring the draft in chamber 11 back to the desired point so as to again return switches 21 and 22 to their neutral position. If draft varies in the opposite direction to that just described so as to cause oscillation of disk 20 in a counterclockwise direction from that shown in Fig. 2, then contacts will be broken in switch 21 and will be closed in switch 22. This causes a circuit from L₁ through line 48, switch 47a, lines 49 and 53 to binding post 25 through switch 22, binding post 26, lines 54 and 55 to binding post 46. This will energize the circuit of the control devices in circuit between binding posts 45 and 46 so as to move it in the opposite direction from that which occurs when the circuit is between binding posts 44 and 45. This will again correct the undesirable condition in pressure chamber 11 so as to return arm 19 to its position parallel to arm 35 with the pointers 27 and 40 in registration. This device is so sensitive that movement of the arms corresponding to a variation of one or two one-hundredths of an inch of water column is sufficient to cause actuation of the device.

Obviously by adjustment of knob 39, arm 35 may be moved to different positions corresponding to a different draft which it is desired to maintain and this automatically sets the neutral position of disk 20 so that the device will tend to hold that neutral position because, as above described, every movement of disk 20 caused by a variation of arm 19 away from parallelism with arm 35 will bring about its own adjustment so as to return the parts to the predetermined draft control position.

Referring again to Fig. 5, it will be noted that the "maximum" button is connected by lines 56 and 55 to the binding post 46 and the "minimum" button is connected by lines 57 and 51 to binding post 44. Thus whenever switch 47a is moved to the maximum or minimum buttons the control device moves as far as possible in either of its two directions of movement as selected by the knob 47.

While I have described my device as used in the control of draft, it will be understood that it may be used to control pressure also by substituting for the link 39 a suitable pressure connection such as is disclosed in my copending application Serial No. 383,965, filed March 18, 1941.

What I claim is:

1. A control gauge comprising means responsive to a medium to be controlled, an arm oscillatable about a point on said arm by said means, a plate oscillatable about said arm as an axis, an

arm engaging said plate at a point spaced from the center thereof, means for setting said arm in various adjusted positions, and a control member actuated by movement of said plate responsive to relative movement between said arms.

2. A control gauge comprising means responsive to a medium to be controlled, an arm oscillatable by said means, a plate oscillatable about said arm as an axis, a settable arm engaging said plate at a point spaced from the center thereof, and a mercury bulb switch on said plate substantially at right angles to said arm and having contacts connected and disconnected by mercury flow in said bulb responsive to relative movement between said arms.

3. A control gauge comprising means forming a pressure chamber and having a flexible diaphragm wall, an oscillatable shaft, an arm fixed thereto, connecting means for oscillating said shaft responsive to movement of said diaphragm wall, a disk oscillatable about said arm as an axis, two mercury switches positioned on said disk and having contacts of one closed and contacts of the other opened by disk oscillation, and a fixed abutment contacting said disk at a point spaced from its axis.

4. A control gauge comprising means forming a pressure chamber and having a flexible diaphragm wall, an oscillatable shaft, an arm fixed thereto, connecting means for oscillating said shaft responsive to movement of said diaphragm wall, a disk on said arm spaced from said shaft, said disk being oscillatable about said arm as an axis, a mercury switch on said disk and adapted to have its contacts opened and closed by disk oscillation, a pointer oscillatable by said shaft, means counterweighting said arm and said connecting means and said disk and switch and pointer so that these parts are in balance about said shaft, a second arm extending radially from said shaft, a pendulum weight on said second arm, and a fixed abutment contacting said disk at a point spaced from its axis.

5. A control gauge comprising means forming a pressure chamber and having a flexible diaphragm wall, an oscillatable shaft, an arm fixed thereto, connecting means for oscillating said shaft responsive to movement of said diaphragm wall, a disk on said arm spaced from said shaft, said disk being oscillatable about said arm as an axis, a mercury switch on said disk and adapted to have its contacts opened and closed by disk oscillation, means counterweighting said arm and said connecting means and said disk and switch so that these parts are in balance about said shaft, a second arm extending radially from said shaft, a pendulum weight on said second arm, and a fixed abutment contacting said disk at a point spaced from its axis.

6. A control gauge comprising means forming a pressure chamber and having a flexible diaphragm wall, an oscillatable member, connecting means for oscillating said member responsive to movement of said diaphragm wall, a member fixed relative to said oscillatable member, means for holding said last named member in various adjusted positions, a disk carried by said oscillatable member, said disk being oscillatable about an axis, means connected with said fixed member abutting said disk at a point spaced from the axis thereof, whereby said disk is oscillated by relative movement between said members, and a control member responsive to disk oscillation.
